FIG. 7.

INVENTOR.
Harry Holdsworth.
BY *L. A. Clegg*
ATTORNEY

UNITED STATES PATENT OFFICE.

HARRY HOLDSWORTH, OF OTEEN, NORTH CAROLINA.

GARMENT SUPPORTER.

Application filed November 10, 1925. Serial No. 68,202.

This invention relates to garment attaching devices whereby two garments or two parts of the same garment may be secured in adjusted relation.

More particularly the invention relates to a device for attaching infants' stockings to diapers, women's stockings to drawers or camisoles, women's drawers or bloomers to waists or camisoles or other like connection.

One important object of the present invention is to improve the general construction of devices of this character.

A second important object of the invention is to provide an improved device of this character which is of such construction as to readily lend itself to manufacture from non-rustable materials, the body being preferably made of rubber or the like while the remainder of the device may be made of non-oxidizable metal, celluloid, or metal varnished, japanned or covered with celluloid, pyroxylin or some similar substance to prevent oxidization.

A third object of the invention is to provide an improved device of this character which is small, simple in construction and which possesses no parts liable to get out of order.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a face view of one form of the device showing the parts assembled.

Figure 2 is a side view thereof.

Figure 3 is a face view of a modified form of the device.

Figure 4 is a section on the line 4—4 of Figure 3.

Figure 5 is a similar section showing a second modification.

Figure 6 is a face view of a third modification.

Figure 7 is a section on the line 7—7 of Figure 6.

In the embodiment of each form of the invention herein illustrated there is provided a body portion 10 which is prefer-

ably made of fabric, rubber or the like so that, if desired it may be sewed or otherwise secured to a garment. However, I do not restrict myself to the use of fabric or rubber or to securing this part of the device to a garment. In fact this part may be made of wood, metal, celluloid or any other desirable material. At each end of this body 10 there is provided a button 11 preferably of ovate form although variants to such form may be used.

In connection with these buttons there is provided a closed loop 12 the ends of which are shaped to fit beneath the heads of the buttons 11 while the intermediate portions are bowed as at 13 to produce a spring action tending to draw the loop ends toward each other.

It is preferred, for ease of use, that one of the two members, preferably the first, shall be flexible and in use a part of one garment is placed over a button and one end of the loop engaged thereover while part of a second garment or a second part of the same garment is placed over the second button and the remaining end of the loop is engaged thereover. Thus the two garments will be securely yet detachably connected.

In order to prevent loss of the loop the sides of the body may be slotted as at 14 and small loops 15 may be run through such slots and around the sides of the loop 12.

Another method of accomplishing the same object is to lead a single endless band 16 through the body transversely thereof, the ends of this band receiving the side portions of the loop 12.

A still further modification consists in separating the loop 12 into two parts 12' and 12'' and pivotally connecting them to a centrally disposed hinge piece 17.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

Having thus described the invention, what is claimed as new, is:

1. In combination, a base, a pair of spaced buttons on said base, and a loop having end portions adapted to fit around the shanks of both said buttons when engaged on the buttons.
2. In combination, a base, a pair of spaced buttons on said base, and a loop having end portions adapted to fit around the shanks of both said buttons when engaged on the buttons, the middle portion being bowed to provide spring means to draw the ends of the loop toward each other.
3. In combination, a base, pair of spaced buttons on said base, and a loop having end portions adapted to fit around the shanks of both said buttons when engaged on the buttons, said base being formed of flexible material such as rubber or the like.
4. In combination, a base, a pair of spaced buttons on said base, a loop having end portions adapted to fit around the shanks of both said buttons when engaged on the buttons, said base being formed of flexible material such as rubber or the like, the middle portion being bowed to provide spring means to draw the ends of the loop toward each other.
5. In combination, a base, a pair of spaced buttons on said base, a loop having end portions adapted to fit around the shanks of both said buttons when engaged on the buttons, and means to movably secure the loop to the base.
6. In combination, a base, a pair of spaced buttons on said base, a loop having end portions adapted to fit around the shanks of both said buttons when engaged on the buttons, the middle portion being bowed to provide spring means to draw the ends of the loop toward each other, and means to movably secure the loop to the base.
7. In combination, a base, a pair of spaced buttons on said base, a loop having end portions adapted to fit around the shanks of both said buttons when engaged on the buttons, said base being formed of flexible material such as rubber or the like, and means to movably secure the loop to the base.
8. In combination, a base, a pair of spaced buttons on said base, a loop having end portions adapted to fit around the shanks of both said buttons when engaged on the buttons, said base being formed of flexible material such as rubber or the like, the middle portion being bowed to provide spring means to draw the ends of the loop toward each other, and means to movably secure the loop to the base.

In testimony whereof I affix my signature.

HARRY HOLDSWORTH.
